UNITED STATES PATENT OFFICE.

CHARLES CORDIER, OF GLENDALE, NEW YORK, ASSIGNOR, BY MESNE ASSIGNMENTS,
TO WESTINGHOUSE ELECTRIC & MANUFACTURING COMPANY, A CORPORATION
OF PENNSYLVANIA.

SAFETY SWITCH BOX.

Application filed September 19, 1919. Serial No. 324,811.

To all whom it may concern:

Be it known that I, CHARLES CORDIER, a citizen of Germany, and a resident of Glen-
dale, Long Island, in the county of Queens
5 and State of New York, have invented a
new and useful Improvement in Safety
Switch Boxes, of which the following is a
specification.

My invention relates to switch boxes and
10 particularly to safety switch boxes.

The object of my invention is to provide
a two-compartment safety switch box that
shall be inexpensive to construct and that
15 shall have simple and effective door-inter-
locking devices.

In practicing my invention, I provide a
switch box, the hinged door to the fuse com-
partment of which is provided with a pro-
jection having a cam face that is concentric
20 with the axis of the switch-operating device.
The switch-operating device is of such shape
that it constitutes a cam member for co-
operation with the projection to preclude
moving the door even a slight distance
25 towards its open position when the switch
is closed and to preclude closing the switch
when the door is open. With this arrange-
ment, the door remains entirely closed when
the switch is closed, thus ensuring complete
30 safety to the operator.

In the accompanying drawings, Figure 1
is a top plan view of a safety switch box
embodiment of my invention; Fig. 2 is a side
35 view, partially in elevation and partially in
section, of the switch box shown in Fig.
1; and Fig. 3 is an end view, partially in
section and partially in elevation, of the
switch box shown in Figs. 1 and 2.

A switch box 1 comprises, in general, a
40 rectangular metallic casing or box 2 hav-
ing an open top and small circular openings
3 and 4 in the sides and bottom thereof, re-
spectively, to receive the leading-in con-
ductors. A hinged cover 5 is secured to a
45 portion of the top of the box and a cover
6 is secured, by screws 7 and a sealing de-
vice 8, to the remaining portion of the top
of the box. A barrier 9 is disposed between
the door 5 and the cover 6 to separate the
50 box into two compartments.

An insulating block 10, of porcelain or
other suitable material, is disposed in the
bottom of the box and is provided with fuse
receptacles 11 at one end thereof and a knife-
55 blade switch 12 at the other end thereof.

A rod 13 is journaled in the sides of the box
at the points 14 and 15 and is of such shape
as to constitute a fulcrumed member hav-
ing a cam portion 16 and a handle portion
17 that extends outside the box at one side. 60

The switch 12 comprises pivotal contact
members 18, jaw members 19, knife-blade
members 20 and a bar 21 of insulating ma-
terial for operatively securing the knife-
blade members together. A projection 22 65
is secured to the bar 21, and a spring 23 is
disposed between the projection 22 and a
washer 24 that is mounted on one side of
a bolt 25, the other end of which passes
loosely through the projection 22 and is 70
pivotally secured to the fulcrumed portion
of the rod 13. This constitutes a resilient
connection between the switch and the oper-
ating member thereof to permit quick opera-
tion of the switch. 75

A projection 26 is mounted on the hinged
door 5 and extends, through a small open-
ing in the barrier 9, into the switch com-
partment of the box. The projection 26
has a portion 27 having a cam face that is 80
concentric with the upper surface of the cam
portion 16 of the rod 13. A projection 28
is disposed at the side of the box and has
an opening 29 therein to receive a padlock
(not shown) for the purpose of locking the 85
handle 17 in the open position of the switch.
The sealing device 8 comprises a projection
that is secured to one end of the box 2 and
extends through an opening 30 in the cover
6 and has an opening therein to receive a 90
lead seal or a padlock, as desired.

When the door 5 is in the position shown
in Fig. 2 of the drawings, the portion 27
of the projection 26 engages the upper side
of the cam portion 16 and thus precludes 95
moving the door 5 toward its open position,
even a relatively short distance. However,
since the cam surfaces are concentric with
respect to each other, the member 13 may
be turned to the position shown in the 100
broken lines in Fig. 2 and thus the door 5
may be raised to the position shown in the
broken lines to permit access to the fuse
compartment of the box. In order to gain
access to the switch compartment of the 105
box, it is necessary to break the seal and to
remove the screws 7 which, of course, should
be done only by an authorized person.
Since the portion 16 engages the cam face 27,
it will be seen that the switch 12 cannot be 110

closed so long as the door 5 is in its open position but the closing of the switch automatically closes the door. When the switch 12 is again in its closed position, the door 5 cannot be moved toward its open position until the switch is opened.

From the foregoing it will be understood that the rod 13 serves the double purpose of the switch-actuating device and an interlock that so co-operates with the concentric projection on the door member as to effectively preclude a relatively slight movement of the door when the switch is in its closed position and thus removes all danger of an operator inserting conductive devices under the door and thereby endangering himself when the switch is closed.

My invention is not limited to the specific structure illustrated but is adapted to be variously modified without departing from the spirit and scope thereof, as set forth in the appended claims.

I claim as my invention:

1. The combination with a switch box having two compartments, a fuse in one compartment and a switch in the other compartment, of a hinged door for the fuse compartment, a projection on the hinged door extending into the switch compartment, and an actuating device for the switch comprising a one-piece rod extending through, and pivoted in, an opening in the side of the box and having such shape as to co-operate with the projection on the door to preclude moving the door when the switch is closed and to preclude closing the switch while the door is open, the portion of the rod within the box being of such shape that it may be inserted through the said opening.
2. The combination with a switch box having two compartments, a fuse in one compartment and a switch in the other compartment, of a hinged door for the fuse compartment, a projection on the hinged door extending into the switch compartment, and a single rod so bent as to constitute an actuating device for the switch and for co-operating with the projection on the door to prevent moving the door when the switch is in its closed position.
3. In a switch box, the combination with a door having a projection thereon, of a rod having substantially uniform cross-section throughout and being bent to form a switch-operating handle and to form a projection for co-operating with the projection on the door to preclude moving the door when the switch is closed.
4. In a switch box having a door, the combination with a knife-blade switch, of a rod having substantially uniform cross-section throughout and extending across the box and through one side thereof, said rod being of such shape as to constitute a handle, two

bearing portions, a portion for connection to the switch and a cam portion for interlocking the switch with the door of the box.

5. A switch box comprising a hinged door for one portion of the box, a removable door for another portion of the box, means for securing the removable door in position, a fuse mounted in that portion of the box having the hinged door, a knife-blade switch mounted in the other portion of the box, a barrier between the two portions of the box, means carried by the door and projecting into the portion of the box containing the switch, an actuating device for the switch comprising a one-piece rod extending into the last said portion of the box and being of such shape as to constitute a cam for co-operating with the projection to preclude opening the door so long as the switch is closed and closing the switch so long as the door is open.

6. A switch box comprising a hinged door, a switch, an operating device for the switch, and a projection on the hinged door having an arcuate cam face concentric with the axis of the operating device when the door is in closed position for co-operating therewith to preclude moving the door towards its open position when the switch is closed.

7. A switch box comprising a hinged door, a rod pivotally mounted in the box and having a handle portion and a cam portion, and a projection on the hinged door having an arcuate cam face normally concentric and co-operating with the cam portion of the rod.

8. A switch box comprising a hinged door, a switch, an operating device for the switch, and a projection on the hinged door having an arcuate cam face normally concentric with the axis of the operating device to co-operate therewith to preclude moving the door towards its open position when the switch is closed and to preclude closing the switch while the door is open.

9. The combination with a box having a cover and a bearing opening in the side of the box and a switch within the box, of an operating rod having a portion extending interiorly of the box through the said opening, the said portion within the box being bent to form a crank by which the switch is actuated and a cam and journals adjacent opposite sides of the box, the said cam being so offset from the axis of rotation of the rod that it co-operates with the said cover for retaining the cover in closed position so long as the switch is in closed position, and the switch in open position so long as the cover is open.

In testimony whereof, I have hereunto subscribed my name this third day of September, 1919.

CHARLES CORDIER.
